UNITED STATES PATENT OFFICE

WILLIAM HENRY SANDERS, OF GASTONIA, NORTH CAROLINA

FLYER PRESSER

Application filed November 17, 1931. Serial No. 575,676.

This invention relates to flyer pressers used in the preparation of textile fibres for placing the slub or rove upon a bobbin. More particularly this invention effects an improvement in the flyer presser with the object of minimizing the losses in operation that result from jamming or breaking of the yarn or rove as it is guided through the flyer.

In the operation of winding bobbins it is customary to feed thread, for example, along one arm of the flyer, a Y-shaped body that rotates around the bobbin. In some types of flyer this arm is constructed as a solid rod along the length of which is a groove to guide the thread. In other types, this arm of the flyer is hollow and through it the thread is passed to the free end of the arm. In this latter type it is customary to provide a narrow slit to facilitate the placement 20 of the thread.

It is customary also to provide the attachment, known as a flyer presser, at the free end of the threaded arm of the flyer. This attachment comprises a finger rotatable 25 about that arm and serving to guide and to tension the thread inwardly toward the bobbin about which the flyer revolves as a whole. The flyer presser essentially is pivoted at the end of the threaded arm of the flyer but often 30 is extended upwardly from this pivot to embrace the flyer arm in a bearing at some higher point also.

It is to the construction and operation of an improvement in flyer pressers of these 35 general types that this invention is directed. It is an object of this invention to operate and to construct such flyer pressers so that the thread, rove or the like will not be interrupted in its passage by jamming and 40 breaking at the openings, bearings or grooves of the flyer arm and presser. Specifically this invention is directed to obtaining such co-operation between the flyer and the flyer presser that the thread may not balloon, or 45 accumulate such slack as to become entangled

in the presser bearing nor to rise along the groove or slot of the threaded arm and become involved in the rotating parts by reason of the dust and lint that collect. A further object of the invention is the provision 50 of means to facilitate threading the flyer.

In an embodiment of this invention selected for the purpose of a specific illustration, there are provided one or more fingers extending inwardly below the presser bearing, these fingers constituting anti-balloonning means, or means to limit the accumulation of slack in the thread and to prevent the rising of the thread to a position where it could become entangled in the presser bearing 55 or could leave the guide in the flyer arm. One form is found in the provision of two such fingers depending from the presser bearing, their free ends inclined toward each other. Preferably between the extremities of the 60 fingers a narrow opening is left sufficient for the passage of the material being wound when guided inwardly between the converging fingers in threading the flyer.

The above and other features are described 70 and claimed in the following specification and claims and illustrated in the accompanying drawings, in which:

Figure 1 represents a front elevation of the 75 flyer and presser;

Figure 2 represents a side elevation of the lower part of the presser and the thread carrying arm of the flyer; and

Figure 3 represents a bottom view of the 80 thread carrying arm of the flyer, and the presser with the thread protecting fingers referred to.

In these drawings numerals 1 and 2 respectively designate the balance arm and the 85 hollow or slotted thread guiding arm of the usual flyer. Numeral 3 designates the usual tension bar parallel to the arm 2 and adapted to rotate partially around said arm. The usual presser finger 4, is shown extending 90

inwardly at right angles from the lower end of the supporting rod 3.

The junction of the presser finger 4 with the lower end of the supporting rod 3, is shown as a band 5, partially encircling the end of arm 2 to provide swivel play of the presser about said arm 2. An opening left in this partially encircling band or swivel bearing normally is toward the outer face of 10 the flyer arm 2, approximately opposite the usual guide slot or groove 10 found in that arm. The limits of rotation of the presser and of the position of this opening in the swivel band will be determined in a simple 15 way by lugs 6 at the upper bearing of tension arm 3, such lugs being either integral with the structure of the arm and bar or secured to them.

Usually in the operation of flyers of this 20 type there occur frequent breaks in the material being wound. It is found that this is a result of the thread leaving the slot or groove 10 of the arm 2 or becoming entangled in the lower swivel bearing of the presser 25 finger or becoming caught with the dust and lint that accumulate along the guiding groove of arm 2.

This invention is directed to preventing the thread from ballooning, or in other 30 words, from leaving the groove at the bottom of the arm 2 in its passage to the presser finger and to prevent its becoming entangled in the swivel bearing at the end of arm 2.

For this purpose one or more fingers 7, 35 constituting anti-ballooning means, are secured to the band 5 near the end or ends where the band is left open opposite the thread groove at the end of arm 2. In the illustration shown two such fingers are 40 shown. These extend downwardly and then turn inwardly at approximately right angles to below the center of arm 2, converging so that the free ends of these fingers 7 nearly meet at opening 8 therebetween, and are 45 spaced from the presser. The dimensions of these fingers will vary according to the circumstances of a given situation. For illustration they may be taken to extend downwardly below the end of arm 2 a quarter of 50 an inch and then turn inwardly the same distance, while their horizontal portions converge to a thirty-second of an inch opening. Obviously the nature of the material treated will introduce variations requiring but or 55 dinary skill.

A further variation of the embodiment shown would be had by extending the fingers downwardly, but minimizing or eliminating the inward horizontal extension, and causing 60 the downward portion to comprise the narrow slot for threading.

Likewise the mode of attachment of the fingers 7 to the band 5 will vary. They may, for example, be cast integrally with the 65 presser or may be welded, soldered, forged,

bolted or screwed to the band 5. They may be so attached to flyers already constructed.

It is clear that in operation the thread passes from the bottom of the arm 2 out along the presser finger, and that any slack or deviation of the thread at that point will be fended or warded by the fingers so that the thread may not leave the guiding slot or groove of arm 2, nor rise to a point where it would be caught in the swivel bearing formed by band 5 about the end of arm 2. Preferably the opening 8 will be thrown a bit to one side of the groove 10, by adjustment of the fingers 7 or by the construction of the lugs 6 to attain that result when the flyer 75 is in operation.

Other embodiments of my invention would comprise forming the fingers of different lengths and placing the opening at some other point than below the center of arm 2. And since this opening is to facilitate threading the presser finger, the opening 8 may be reduced or enlarged in certain embodiments of the invention without losing the advantages resulting from preventing the breaking of the thread due to the placing of the guide as contemplated by this invention.

Likewise it will be clear that other forms of a unitary finger than that last described may be adapted within this invention to the purpose of preventing the deviation of the thread to a point where it may break. It is apparent from this description and the drawings that by this invention the thread is hindered from rising above the bottom of the groove or slot 10 and from reaching the level of the bearing formed by band 5. By thread is meant also yarn, rove or any other filament material as may be passed through flyers of the type described.

While specific illustrative terms have been employed to present an operative-embodiment of this invention, no restriction thereby is intended beyond such as necessarily are imposed within the terms of the claims.

I claim:

1. A flyer comprising a thread-carrying arm in combination with a presser finger extending from a swivel bearing about said arm, and a guide extending from the swivel bearing to a point below the same and spaced from the same and from said presser, the terminal portion of the guide constituting anti-ballooning means and being spaced from the presser.

2. In a flyer having a thread-carrying arm with an outlet for the thread, and a presser swivel on said arm, a filament guide extending under said arm and immediately below said thread outlet and said presser, the terminal portion of said filament guide constituting anti-ballooning means and being spaced from said presser.

3. In a flyer having a thread-carrying arm and a presser pivotally mounted on said arm,

- a filament guide comprising a plurality of fingers depending from said presser and extending to a point immediately under said arm, the terminal portions of said fingers 5 converging closely together so as to form a narrow opening therebetween and constituting anti-ballooning means, said terminal portions of the fingers being spaced from the presser.
- 10 4. In a flyer having a presser finger extending inwardly from a thread-carrying arm and rotatable about said arm, a plurality of fingers extending below said arm, thence extending inwardly and converging 15 under said arm, so as to form at their terminal portions a narrow opening therebetween, the terminal portions of said portions constituting anti-ballooning means, and being spaced from the presser.
- 20 5. In a flyer having a presser finger extending inwardly from a swivel bearing about a thread-carrying arm of the flyer, and a thread outlet near said bearing, and guide means extending below said thread outlet, 25 thence extending parallel to said presser finger and below said bearing, the terminal portion of said guide means constituting anti-ballooning means and being spaced from said presser.
- 30 6. In a flyer having a presser finger extending inwardly from a swivel bearing about a thread-carrying arm of the flyer, and a thread outlet, a guide extending below said thread outlet and under said bearing and 35 comprising a plurality of fingers converging in the general direction of the presser finger, the terminal portions of said converging fingers constituting anti-ballooning means and being spaced from said presser.
- 40 7. In a flyer having a presser finger extending inwardly from a swivel bearing about a thread-carrying arm of the flyer, and a thread outlet, guide means extending below said thread outlet and under said bearing 45 and comprising a plurality of fingers spaced from said presser finger and having one end converging in the general direction of the presser finger and the opposite end attached to the presser finger, said converging ends terminating so as to nearly meet, and constituting anti-ballooning means, and being spaced from the presser.
- 50 8. In a flyer having a hollow thread-carrying arm with an outlet for the thread 55 and a presser finger swivelly mounted on said arm, a filament guide extending from said presser finger at a location on the far side of said thread-carrying arm from the main length of said presser finger and said 60 guide extending below said outlet and thence extending in the same general direction as the main length of said presser finger.
- 65 9. In a flyer having a hollow thread-carrying arm with an outlet for the thread 65 and a presser finger swivelly mounted on
- said arm, a filament guide comprising a plurality of fingers both extending from said presser finger at a location on the far side of said thread-carrying arm from the main length of said presser finger, and both of 70 said fingers of said guide extending below said outlet and thence extending in the same general direction as the main length of said presser finger.
- In testimony whereof I affix my signature. 75
